RAIL ANCHOR

John P. Heuer, Pittsburgh, Pa.

Application October 6, 1945, Serial No. 620,687

1 Claim. (Cl. 238—321)

1

This invention relates to a rail holder for a railroad rail, and important objects and advantages thereof are to provide a device of the character described, which will secure the rail against longitudinal movement on the ties, which will increase its holding action as forces tending such longitudinal creeping movement increase, which may be readily installed to or removed from a rail, which comprises only two parts, which is simple in its construction and arrangement, durable and efficient in its use, compact, and comparatively economical to manufacture and install.

With the foregoing and other objects in view which will appear as the description proceeds, the invention resides in the novel construction, combination, and arrangement of parts herein specifically described and illustrated in the accompanying drawing, but it is to be understood that changes in the form, proportions and details of construction may be resorted to that come within the scope of the claim hereunto appended.

In the drawing wherein like numerals of reference designate corresponding parts throughout the several views:

Figure 1 is a top plan view of a rail holder assembled in place on a rail. Figure 2 is a side elevational view thereof. Figure 3 is a sectional view on line 3—3, Figure 1. Figure 4 is a top plan view of the clamping members in the assembled positions. Figure 5 is a perspective view of one of the clamping members, and Figure 6 is a bottom plan view of a modified form of clamping member, embodying the present invention.

Referring in detail to the drawing 1 denotes the entire railroad rail, which is of the conventional construction and comprises the head 2, the web 3, and the base 4. The rail is secured to the tie 5 and tie plate 6, by means of spikes 7, in the usual manner well known in the art to which the invention appertains.

The improved rail holder comprises a pair of identical clamping members, respectively indicated at 8 and 9. Each of the clamping members consists of an oblong, flat, rectangularly-shaped supporting plate 10, the outer side edge margin of which is formed to provide an upwardly disposed, hook-shaped clamping jaw 11 extending along the entire length thereof. A securing flange 12 of similar length is formed integral with the inner side edge of each of the clamping members, and depends at an angle of approximately forty-five degrees with respect to the horizontal disposition of the supporting plate.

Each of the clamping members 8 and 9 is 55 rail 1 to dispose the forward abutting end of the

2

provided with an elongated, longitudinally extending connecting slot 13, which is disposed at the juncture of the supporting plate 10 with the associated securing flange 12. The slot is of a length approximating one-half the length of the clamping member and has an open end. The inner side wall 14 of the slot, disposed toward the securing flange, extends at a slight angle relatively to the straight outer side wall 15 of the slot, whereby said slot gradually decreases in width from its open end towards its closed end, as clearly illustrated in Figure 5.

In assembling the improved rail holder on the rail 1, the pair of clamping members 8 and 9 are arranged in opposed relation to each other beneath the rail base 4, whereby the open end of the slot 13 in the clamping member 8 will be opposed and adjacent to the open end of the slot in the other clamping member 9. The clamping jaw 11 of the clamping member 8 is positioned to engage and overlap one side edge margin of the rail base 4, and the clamping jaw of the clamping member 9 is placed to engage and overlap the other side edge margin of the rail base, as clearly shown in Figure 1.

The clamping member 8 is positioned in advance of the clamping member 9, and the forward end of the former abuts against the tie plate 6. The clamping member 9 is advanced 30 in the forward direction until the slot 13 thereof engages the clamping member 8 along the line of juncture of the supporting plate 10 with the associated flange 12. Conversely, but in like manner, the slot 13 in the clamping member 8 will engage the clamping member 9, as clearly shown in Figure 4.

Such inter-locking engagement of the clamping members 8 and 9 is effected by forcibly driving the clamping member 9 into its engagement with the advanced clamping member 8. Due to the angular disposition of the slot walls 14, the forcible inter-locking engagement of the clamping members, as stated, will draw the latter toward each other in the transverse direction, whereby the 45 clamping jaws 11 will be securely clamped against the respective side edges of the rail base 4.

As shown in Figure 6, the connecting slot 13 may be provided with a toothed angular wall 16, and the under surface of the juncture of the plate 10 and flange 12 may be roughened, as indicated at 17. By such construction the interlocking engagement of the clamping members may obviously be greatly increased.

The improved rail holder is assembled on the

clamping member 8 in the direction of the rail traffic. It will be apparent that the force of traffic travel, tending to shift the rail 1 longitudinally, will be imparted to the clamping members to force the latter into further inter-locking engagement, thereby increasing the gripping or clamping action of the jaws 11 on the rail base 4 to securely hold the rail against longitudinal creeping movement on the ties. Any necessary number of rail holders may be installed on each length of rail, and said holders may be installed in positions to function on rails employed for traffic in one or both directions.

What I claim is:

The combination with a railroad track rail, 15 of a pair of similar clamping members arranged in opposed relation to each other, each of said members comprising a flat oblong horizontally disposed supporting plate positioned under the base of the rail, each of said plates carrying a clamping jaw extending along the outer side edge thereof and engaging and overlapping respective side edges of the base of the rail, each of said plates carrying a securing flange extending along the inner edge thereof and depending at an angle 20 relatively to said plate, each of said members having an open longitudinally disposed slot of substantial length formed at the juncture of said

5
10

plate with said flange, said slot having an angularly disposed wall at the flange side thereof decreasing the width of said slot from the outer end toward the inner end thereof, said angularly disposed wall being provided with teeth, said juncture having the underside thereof roughened opposite the slotted end thereof, said juncture of one of said pair of members being engageable in the slot of the other of said pair of members to cause the toothed wall of the slot of one of said pair of members to engage and grip the said roughened juncture of the other of said pair of members for securely interlocking said pair of members together on the base of the rail.
